UNITED STATES PATENT OFFICE.

ORAL F. RAINBOLT, OF LYONS, INDIANA.

FRICTION SAFETY STOP.

Application filed July 28, 1924. Serial No. 728,722.

To all whom it may concern:

Be it known that I, ORAL F. RAINBOLT, a citizen of the United States, residing at Lyons, in the county of Greene and State of Indiana, have invented a new and useful Friction Safety Stop, of which the following is a specification.

The present invention relates to safety devices for elevators, lifts, or the like and aims 10 to provide novel means whereby the elevator or lift equipped with the safety device will be automatically stopped in its downward movement to insure against injury to persons riding thereon.

15 An important object of the invention is to provide a device of this character which will operate to gradually retard the movement of the elevator lift, prior to its stopping, thereby eliminating the sudden jar incident to an 20 elevator or lift stopping abruptly.

A still further object of the invention is the provision of a device of this character which will be readily and easily installed on elevators or lifts now in use, eliminating the 25 necessity of making alterations in the elevator or lift construction to apply the device.

With the foregoing and other objects in view which will appear as the description proceeds, the invention resides in the combination and arrangement of parts and in the details of construction hereinafter described and claimed, it being understood that changes 30 in the precise embodiment of the invention herein disclosed, may be made within the 35 scope of what is claimed, without departing from the spirit of the invention.

Referring to the drawings:

Figure 1 is an elevational view disclosing a safety device constructed in accordance 40 with the invention as mounted on an elevator.

Figure 2 is a plan view thereof.

Figure 3 is a sectional view taken on line 3—3 of Figure 1.

Figure 4 is a sectional view taken on line 45 4—4 of Figure 1.

Figure 5 is a sectional view taken on line 5—5 of Figure 2.

Figure 6 is a sectional view taken on line 6—6 of Figure 2.

50 Referring to the drawings in detail, the reference character 5 designates spaced guides which are engaged by the arms 6 carried by the elevator frame to support the elevator against lateral movement.

55 The reference character 7 indicates the

upper beam of the elevator frame and the reference character 8 indicates vertical side bars which have their upper ends secured to the beam 7 and braced against movement, by means of the brace members 9 arranged adjacent to the upper ends of the bars 8. As clearly shown by Figure 1 of the drawings, the lifting cable is indicated at 10 and has connection with the beam 7 through the plates 11 that are bolted to the beam 7 by 60 means of bolts 12.

The safety device forming the subject matter of the present invention includes a horizontal shaft 13 that has one end thereof supported in the bearing 14 mounted on the beam 7, the opposite end thereof operating in the bearing 15 which is mounted on the sliding plate 16 that moves in the guideways 17 positioned on the plate 18 that in turn is mounted on the beam 7.

Threads 19 are formed on the shaft 13 adjacent to one side thereof, while the threads 20 which are disposed in the opposite direction, are arranged on the shaft 13 at the opposite side thereof for purposes to be herein- 70 after more fully described.

Operating through the bearing 15 and positioned on the shaft 13 is a sleeve 21 that carries the beveled pinion 22, which pinion is secured in position on the sleeve at 21 by 80 means of the set screw 23 and as clearly shown by Figure 6 of the drawings, the sleeve is formed with a squared opening to be fitted over the squared extremity 24 of the shaft 13 so that the sleeve may be free to 85 move longitudinally of the shaft 13 and at the same time receive rotary motion therefrom which in turn is imparted to the pinion 22.

The pinion 22 is in mesh with the beveled 90 pinion 25 which is mounted on the shaft 26 that has one end thereof positioned in the socket 27 of the bearing member 15, the opposite end of the shaft 26 being mounted in the bearing 28 carried at the upper end of 100 the arm 29 that is also secured to the sliding plate 16 to the end that when the pinion 22 is moved longitudinally of the shaft, the beveled pinion 25 is also moved in a direction longitudinally of the shaft 13.

Teeth 29 are formed on the periphery of the pinion 25 and are designed to cooperate with the teeth 30 provided on the inner edge of the guide 5 at one side of the elevator way. At one end of the sleeve 21 is a 110

grooved member 31 in which the forked end of the arm 32 moves, which arm 32 has an extension 33 that is connected to the cable 10 at 34, the extension 33 being acted on by 5 the coiled spring 35 that has one end thereof anchored to the plate 18 by means of the eye bolt 36. Thus it will be seen that due to the connection between the extension 33 and cable 10, the pinions 22 and 25 will be 10 normally held in their inactive positions but when the cable breaks under excessive weight, the coiled spring will act to move the extension 33 downwardly and causing the pinions 22 and 25 to move outwardly or 15 towards the guide 5, the teeth of the pinion 25 meshing with the teeth 30 of the guide 5 with the result that rotary movement is transmitted to the shaft 13 through the pinions 25 and 22.

20 A latch member indicated at 37 lies in the path of travel of the extension 33, on its downward movement and engages the extension 33 to hold the same to its active position after it has been moved downwardly by the spring 35. The reference character 38 indicates gripping members which are pivotally mounted at the outer ends of the arms 39 that have cam surfaces 40 which are engaged by the rollers 41 carried 25 on the arms 42 that have their lower ends pivotally connected to the arms 43 that are secured to the beams 8 of the elevator frame.

The upper ends of the arms 42 carry 30 threaded eyes 44 that are mounted on the threaded portions 19 and 20 respectively of the shaft 13 so that as the shaft 13 is rotated, the upper ends of the arms 42 will be moved towards each other, to the end that the rollers 41 are moved towards each 35 other over the cam surfaces 40 causing the outer ends of the arms 39 which carry the gripping members 38 to move towards each other, gripping the guides 5 associated therewith.

40 The arms 39 are pivotally connected at 42' so that movement of the inner ends of the arms 39 will produce a relative movement of the opposite ends of the arms 39, in the opposite directions.

45 These arms 39 are supported by the links 43' that have connection therewith through the eye bolt 44, the upper ends of the links 43' being connected to the eye beam 7, by means of the bolts 45. Coiled springs 46 connect the inner ends of the arms 39 to normally urge the arms towards each other, at their inner ends.

50 It is believed that in view of the foregoing, the operation of the device will be clear and that a further detail description as to the operation of the device is unnecessary, however it might be stated that after the gripping members have been operated to accomplish the purpose of the invention, 55 the lever 46 which has connection with the

shaft 13 may be operated over the ratchet wheel 47 to rotate the shaft 13 in the opposite direction to release the pinion 25 and cause it to disengage the teeth of the guide 5.

I claim:—

1. An automatically operated stop device for an elevator operating between toothed guides and having a lifting cable including a shaft, pinions slidably mounted on the shaft, a pivoted arm having connection with one of the pinions to move the pinions to their active positions, said arm having connection with the cable to normally hold the arm in its inactive position, a spring for moving the arm to its active position, and means controlled by the movements of the shaft for gripping the guides to retard movement of the elevator. 70

2. An automatically operated stop device for an elevator operating between toothed guides and having a lifting cable, pinions slidably mounted on the shaft, said shaft having oppositely disposed threads, means for moving the pinions into engagement with the teeth of the guides when the cable breaks, arms having threaded eyes operating on the threaded portions of the shaft, and gripping members adapted to be moved into engagement with the guides when the arms are moved over the threaded portions 90 of the shaft. 95

3. An automatically operated stop device for an elevator operating between guides, a shaft carried by the elevator, means at one end of the shaft and adapted to be thrown into engagement with one of the guides for rotating the shaft, arms pivotally mounted on the elevator and carrying gripping members at their outer ends, said arms having cam surfaces, pivoted arms having their lower ends disposed between the cam surfaces of the first mentioned arms, to move the arms and cause the gripping members to grip the guides, and said last mentioned arms having eyes removable on the shaft to cause the arms to move when the shaft is rotated. 100 105

4. An automatically operated stop device for an elevator operating between guides, and having an elevating cable, a shaft carried by the elevator, means at one end of the shaft and adapted to be automatically moved into engagement with one of the guides to cause the shaft to rotate, arms pivotally mounted on the elevator, gripping members on the outer ends of the arms and means operating between the arms and mounted on the shaft to move longitudinally thereof for moving the arms and causing the gripping members to grip the guides. 110 115 120

5. An automatically operated stop device for an elevator operating between guides, and having an elevating cable, a shaft mounted on the elevator, said shaft having threaded portions, a shaft operating member, 125 130

member slideable on the shaft and adapted to be moved into engagement with one of the guides for imparting rotary movement to the shaft, means having connection with the cable for moving the shaft operating member to its active positions, arms carrying gripping members pivotally supported by the elevator, and arms having threaded portions moving over the threaded portions 10 of the shaft for moving the first mentioned

arms to cause the gripping members to grip the guides.

In testimony that I claim the foregoing as my own, I have hereto affixed my signature in the presence of two witnesses.

ORAL F. RAINBOLT.
